Filed Aug. 10, 1965, Ser. No. 86,519

Term of patent 14 years

(Cl. D93—3)

Fig. 4.Fig. 5.Fig. 6.FIG. 1 is a perspective view of a chain saw taken from above and the front end, showing our new design; FIG. 2 is a top plan view of the chain saw;

FIG. 3 is a side view thereof, taken from the bottom of FIG. 2;

FIG. 4 is a side view thereof, taken from the top of FIG. 2 and reversed;

FIG. 5 is a front end view taken from the left of FIG. 2;

FIG. 6 is a rear end view taken from the right of FIG. 2; and

FIG. 7 is a bottom plan view taken from the bottom of FIG. 3.

The dominant features of our design reside in the portions shown in full lines.

We claim:

The ornamental design for a chain saw, substantially as shown and described.
